ORVILLE EDWARD WOOLDRIDGE, OF GREENVILLE, ILLINOIS, ASSIGNOR OF ONE-THIRD
TO A. W. KNIGHT AND ONE-THIRD TO C. G. SCOFIELD, OF BRAZIL, INDIANA.

AUTOMATIC STARTER FOR AUTOMOBILES.

1,177,161.

Specification of Letters Patent. Patented Mar. 28, 1916.

Application filed June 26, 1915. Serial No. 36,460.

To all whom it may concern:

Be it known that I, ORVILLE E. WOOLDRIDGE, a citizen of the United States, and a resident of Greenville, in the county of Bond and State of Illinois, have invented a new and Improved Automatic Starter for Automobiles, of which the following is a full, clear, and exact description.

Among the principal objects which the present invention has in view are: to provide means for mechanically cranking an automobile engine; to provide means for manually controlling the same; to provide means for automatically governing the stored power of said cranking means; and to simplify the mechanism and condense the space occupied thereby.

Drawings.—Figure 1 is a cross section of a starter constructed and arranged in accordance with the present invention, the section being taken as on the line 1—1 in Fig. 2; Fig. 2 is a vertical longitudinal section of the apparatus, the section being taken as on the line 2—2 in Fig. 1; Fig. 3 is a horizontal section showing a fragment of the casing of the apparatus and mechanism mounted therein, the section being taken as on the line 3—3 in Fig. 1; Fig. 4 is a detail view in vertical section, the section being taken as on the line 4—4 in Fig. 1.

Description.—As seen in the drawings, two bevel wheels, designated by the numerals 9 and 10, respectively, are rotatively mounted on a short shaft 11, the opposite ends whereof are fixedly mounted in the sides 12 and 13, respectively. The hubs of said wheels are truncated and mutually engaged, as shown best in Fig. 1 of the drawings. The wheels 9 and 10 are independently driven by a coil spring 14, the inner end of which is anchored to the shaft 11, while the outer end is anchored to a pin 15 mounted in the wheel 10.

Suspended between the wheels 9 and 10 is a gear pinion 16, the short shaft 17 of which is provided with a rocking bearing in a slide block 18. Normally the slide block 18 is held by compression springs 19 in spaced relation to both of the wheels 9 and 10. The springs 19 are balanced so that the block 18 and shaft 17 therein are held so that the teeth of the pinion 16 are disengaged from both of said wheels 9 and 10.

Movement is continuously imparted to the pinion 16 through a transmission shaft 20

with which the shaft 17 is connected by a universal joint couple 21 of conventional construction. The opposite end of the shaft 20 is connected with the engine- or crank-shaft 22 through miter gears 23 and 24. The shaft 20, like the engine shaft 22, is rotated at all times, whether by the gear 24 or the wheel 10, in a uniform direction. The pinion 16 is engaged with one or other of the wheels 9 or 10 in correspondence with the movement of the block 18. This movement is controlled manually, suitable operating members being for this purpose attached to eyelets 25 in the ends of the pull rods 26 and 27. The operating members above referred to are disposed adjacent the seat of the driver of the automobile, for convenience of manipulation by him. The engine having the shaft 22 is initially employed to wind the spring 14, which thereafter constitutes the prime mover for the starter herein disclosed. When the rod 26 is drawn upon, the pinion 16 is drawn into engagement with the teeth of the wheel 9. The wheel 9 being operatively engaged with the wheel 10, this is likewise rotated, winding the spring 14 about the shaft 11.

The block 18 is held in the position to which it is manually drawn, by a latch 28, the head 29 whereof enters a socket 30 formed in the side of the block 18, as shown best by dotted lines in Fig. 3 of the drawings. To this end, the latch 28 is moved by a compression spring 31. The spring 31 is housed in a bore 32 formed in a housing 33. The bore 32 is normally closed by a screw plug 34, which plug may be manipulated to be advanced or retracted to vary the strength of the spring 31.

To avoid overwinding the spring 14, and breakage incident thereto, means for automatically releasing the latch 28 is provided. The wedge blade 35 is mounted fixedly on a screw-threaded nut or collar 36, the wedge end of the blade 35 being extended through a perforation 37 in the latch 28, and through corresponding perforations 38 in the housing 33.

From the foregoing it is obvious that if the blade 35 is advanced through said perforations 37 and 38, the latch 28 will be forced up the inclined surface of the blade 35, compressing the spring 31 and withdrawing the head 29 from the socket 30. The disengagement thus effected permits the

springs 19 to reestablish the central position of the shaft 17 and pinion 16.

To move the blade 35 in the manner described is the office of the star wheel 39 and screw 40. The screw 40 has reduced or pintle ends to form bearings for said screw and for the star wheel 39 rigidly secured thereto. The star wheel 39 is rotated by a pin 41, which is set out from the back of the wheel 9 in the path of the wheel 39 to engage each of the teeth successively. Thus the wheel 39 is rotated the distance between the teeth thereof in timed relation to the complete rotation of the wheels 9 and 10. As the wheel 39 and screw 40 connected therewith are rotated, the nut or collar 36 is advanced, extending the blade 35 through the latch 28 to lift the same from the socket 30 in the block 18. The blade 35, remaining in this position, serves to prevent the latch 28 from reentering the socket 30, until, by the reverse rotation of the wheel 39 and screw 40, the blade 35 is drawn from engagement with the latch 28.

The retraction of the blade 35 above described is incident to the release of the wheel 10, which permits the spring 14 to expand, and in expanding, rotate said wheel and the wheel 9 with which it is connected, in a relatively opposite direction to that above set forth. Until so released, the wheel 10 is held stationary by a brake shoe 42. As seen best in Fig. 4 of the drawings, the shoe 42 extends partly about the wheel 10, and is shaped in correspondence with a V-shaped groove 43, with which said wheel is provided.

The brake shoe 42 is constructed from any suitable material, and has mounted in cups formed at the median section thereof, bearing balls 44, shown best in Figs. 1 and 4 of the drawings. A bearing plate 45 is furnished to receive said balls, said plate being mounted on the under side of a housing 46, wherein is formed the runway of the block 18. The plate 45, as shown in Fig. 4 of the drawings, is beveled, the thickened portion thereof being at what may be termed the "far" side of the median plane of the wheel 10, or in the direction of travel of said wheel when driven by the spring 14.

The brake shoe 42 and balls 44 carried thereby are normally held in service by a lever 47. The lever 47 is pivotally mounted by a pin 48 in a bracket 49. The lever 47 is provided with a latch head 50. The head 50 has an inclined face 51, the heel or lower edge whereof normally rests above or in line with one side of the block 18. The toe or high point of the face 51 extends into the path of said block 18, to be engaged thereby when the same is moved to that end, and to be forced backward, carrying the shoe 42 in the direction indicated by the arrow *a* in Figs. 3 and 4 of the drawings. This action

of the block 18 upon the latch head 50, lever 47 and brake shoe 42 occurs when the operator draws upon the rod 27 to crank the shaft 22 to start the engine provided therewith.

Operation.—Having a starter constructed and arranged as above described and as shown in the accompanying drawings, the operation is as follows:—Some time during the operation of the shaft 22 the driver of an automobile draws the rod 26 in such manner that the block 18 is moved to a position where the pinion 16 engages the wheel 9, and the latch head 29 is forced into the socket 30 by the spring 31. Power is now transmitted from the shaft 22 through the gears 24 and 23 and shaft 20 to rotate the wheels 9 and 10. The rotary movement imparted to the wheel 10 to wind the spring 14 is in the direction indicated by the arrow *a* in Fig. 4 of the drawings, or in a direction to release the braking strain of the shoe 42. So long as the wheel 10 is turned in this direction, the shoe 42 does not retard or grip said wheel.

The pinion 16 being thus held in engagement with the wheel 9, the wheels 9 and 10 are rotated until the pin 41 has moved the star wheel 39 and screw 40 connected therewith to advance the nut or collar 36 and the blade 35 to a position where the latch 28 and head 29 thereof are lifted from the socket 30 in the block 18. This action permits the reestablishment of the block 18 by the springs 19 to the central position for said pinion, between and disengaged from the wheels 9 and 10, as shown in Fig. 1 of the drawings. When the wheels 9 and 10 are thus released, the spring 14 carries a retractive force on said wheels 10 and 9, which is immediately arrested by the brake shoe 42, the balls 44 of which now move backward over the plate 45 and toward the thickened edge thereof. This action jams said balls below said plate, setting the shoe 42 into rigid engagement in the V-shaped slot 43 of the wheel 10. In this position, the spring 14 is held in what may be designated as a "charged" condition. When now, the automobile having been brought to a stand and the motor stopped, the chauffeur, to crank the shaft 22 and start his motor, draws upon the rod 27 and moves the pinion 16 into engagement with the heel 10. It will be observed that prior to the block 18 engaging the head 50 of the lever 47, the teeth of the pinion 16 are fully engaged with the teeth of the wheel 10. The full movement of the block 18 in the direction indicated shifts the brake shoe 42 backward, or in the direction indicated by the arrow *a* in Fig. 4 of the drawings. The wheel 10 is now at liberty to move with the spring 14 in the direction indicated by the arrow *b* in Fig. 4, thereby rotating the pinion 16, shaft 120

20, gears 23 and 24, and shaft 22, in the direction formerly pursued. Though the wheels 9 and 10 are now rotated in a direction relatively opposite to that imparted 5 when driven by the shaft 22, the rotation of said shaft 22, when driven by the spring 14, is the same.

It will be noted that as the movement of the rod 27 is controlled manually, the duration of operation is likewise optional. If the engine connected with the shaft 22 starts rapidly, the operator releases said rod 27 to permit the springs 19 to place the pinion 16 centrally, moving thereby the block 18 15 to permit the brake shoe 42 to grip and hold the wheel 10 against further rotation, which would needlessly exhaust the spring 14.

Claims:

1. A starter as characterized, comprising 20 a transmission mechanism for operative connection with the crank shaft of an internal combustion engine and embodying a gear pinion; means manually operative for laterally shifting said gear pinion; a plurality of 25 transmission gear wheels adapted for engagement with said pinion; and a prime mover operatively connected with said wheels to drive the same in one direction only.

2. A starter as characterized, comprising a transmission mechanism for operative connection with the crank shaft of an internal combustion engine and embodying a gear pinion; means manually operative for 30 laterally shifting said gear pinion; a plurality of transmission gear wheels adapted for engagement with said pinion; a prime mover operatively connected with said wheels to drive the same in one direction only; and automatic means for normally maintaining said pinion between said wheels and disengaged 35 therefrom.

3. A starter as characterized, comprising a transmission mechanism for operative connection with the crank shaft of an internal combustion engine and embodying a gear pinion; means manually operative for laterally shifting said gear pinion; a plurality of 40 transmission gear wheels adapted for engagement with said pinion; a prime mover operatively connected with said wheels to drive the same in one direction only; automatic means for normally maintaining said pinion between said wheels and disengaged 45 therefrom; and means for locking said pinion in engaged relation with one of said wheels to rotate the same in a direction opposite to that to which it is moved by said prime mover.

4. A starter as characterized, comprising a transmission mechanism for operative connection with the crank shaft of an internal combustion engine and embodying a gear pinion; means manually operative for 50 laterally shifting said gear pinion; a plu-

rality of transmission gear wheels adapted for engagement with said pinion; a prime mover operatively connected with said wheels to drive the same in one direction only; automatic means for normally maintaining said pinion between said wheels and disengaged therefrom; a floating shaft mounted in said pinion; a sliding block forming a bearing for said shaft; a latch and socket adapted to operatively engage 70 said block to hold the same adjusted to maintain the engaged relation of said pinion and one of said wheels, for driving said wheel from the internal combustion engine with which said transmission mechanism is 75 engaged.

5. A starter as characterized, comprising a transmission mechanism for operative connection with the crank shaft of an internal combustion engine, and embodying a gear pinion; means manually operative for laterally shifting said gear pinion; a plurality of transmission gear wheels adapted for engagement with said pinion; a prime mover operatively connected with said wheels to 80 drive the same in one direction only; automatic means for normally maintaining said pinion between said wheels and disengaged therefrom; a floating shaft mounted in said pinion; a sliding block forming a bearing 85 for said shaft; a latch and socket adapted to operatively engage said block to hold the same adjusted to maintain the engaged relation of said pinion and one of said wheels, for driving said wheel from the internal 90 combustion engine with which said transmission mechanism is engaged; and means for gradually releasing said latch.

6. A starter as characterized, comprising a transmission mechanism for operative connection with the crank shaft of an internal combustion engine and embodying a gear pinion; means manually operative for laterally shifting said gear pinion; a plurality of transmission gear wheels adapted for engagement with said pinion; a prime mover operatively connected with said wheels to 100 drive the same in one direction only; automatic means for normally maintaining said pinion between said wheels and disengaged 105 therefrom; a floating shaft mounted in said pinion; a sliding block forming a bearing for said shaft; a latch and socket adapted to operatively engage said block to hold the same adjusted to maintain the engaged relation of said pinion and one of said wheels, for driving said wheel from the internal 110 combustion engine with which said transmission mechanism is engaged; and means for gradually releasing said latch, said 115 prime mover operatively connected with the engaged wheel.

7. A starter as characterized, comprising a transmission mechanism for operative engagement with the crank shaft of an in- 120

ternal combustion engine and embodying a gear pinion; means manually operative for laterally shifting said gear pinion; a plurality of transmission gear wheels adapted 5 for engagement with said pinion; a prime mover operatively connected with said wheels to drive the same in one direction only; automatic means for normally maintaining said pinion between said wheels and 10 disengaged therefrom; a floating shaft mounted in said pinion; a sliding block forming a bearing for said shaft; a latch and socket adapted to operatively engage said block to hold the same adjusted to 15 maintain the engaged relation of said pinion and one of said wheels, for driving said wheel from the internal combustion engine with which said transmission mechanism is engaged; means for gradually releasing said 20 latch, said means embodying a star wheel, a screw driven thereby, and a nut mounted on said screw and having a wedge blade for releasing said latch; and means operatively connecting said star wheel and said gear 25 wheel.

8. A starter as characterized, comprising a transmission mechanism for operative engagement with the crank shaft of an internal combustion engine and embodying a gear pinion; means manually operative for laterally shifting said gear pinion; a plurality of transmission gear wheels adapted for engagement with said pinion; a prime mover operatively connected with said wheels to 30 drive the same in one direction only; automatic means for normally maintaining said pinion between said wheels and disengaged therefrom; a floating shaft mounted in said pinion; a sliding block forming a bearing 35 for said shaft; a latch and socket adapted to operatively engage said block to hold the same adjusted to maintain the engaged relation of said pinion and one of said wheels, for driving said wheel from the internal 40 combustion engine with which said transmission mechanism is engaged; means for gradually releasing said latch, said means embodying a star wheel, a screw driven thereby, and a nut mounted on said screw 45 and having a wedge blade for releasing said latch; and a pin laterally extended from said gear wheel to engage said star wheel to move the same intermittently and in correspondence with the rotation of said gear 50 wheel.

9. A starter as characterized, comprising a driven member embodying oppositely-disposed gear teeth in spaced relation; a stationary shaft for rotatively supporting said member; a coil spring connecting said shaft and member; transmission means operatively connected with the crank shaft of an internal combustion engine and embodying a floating gear pinion disposed between the 60 teeth of said member and in spaced relation 65 to thereto, said pinion having teeth for engaging the teeth of said members; and means for automatically maintaining said pinion in disengaged relation to said teeth.

10. A starter as characterized, comprising 70 a driven member embodying oppositely-disposed gear teeth in spaced relation; a stationary shaft for rotatively supporting said member; a coil spring connecting said shaft and member; transmission means operatively 75 connected with the crank shaft of an internal combustion engine and embodying a floating gear pinion disposed between the teeth of said member and in spaced relation thereto, said pinion having teeth for engaging 80 the teeth of said member; means for automatically maintaining said pinion in engaged relation to said teeth; and selective means manually operative for shifting said pinion to engage one set of said teeth to 85 drive said member from said crank shaft, to wind said spring.

11. A starter as characterized, comprising 90 a driven member embodying oppositely-disposed gear teeth in spaced relation; a stationary shaft for rotatively supporting said member; a coil spring connecting said shaft and member; transmission means operatively 95 connected with the crank shaft of an internal combustion engine and embodying a floating gear pinion disposed between the teeth of said member and in spaced relation thereto, said pinion having teeth for 100 engaging the teeth of said member; means for automatically maintaining said pinion in engaged relation to said teeth; selective means manually operative for shifting said pinion to engage one set of said teeth to 105 drive said member from said crank shaft, to wind said spring; and automatic means for locking said member when said pinion is disengaged therefrom.

12. A starter as characterized, comprising 110 a driven member embodying oppositely-disposed gear teeth in spaced relation; a stationary shaft for rotatively supporting said member; a coil spring connecting said shaft and member; transmission means operatively 115 connected with the crank shaft of an internal combustion engine and embodying a floating gear pinion disposed between the teeth of said member and in spaced relation thereto, said pinion having teeth for engaging 120 the teeth of said member; means for automatically maintaining said pinion in engaged relation to said teeth; selective means manually operative for shifting said pinion to engage one set of said teeth to 125 drive said member from said crank shaft, to wind said spring; automatic means for locking said member when said pinion is disengaged therefrom; and means for releasing said locking means when said pinion is moved to engage the set of teeth on said member to rotate said transmission mecha- 130

nism in correspondence with the crank shaft of said engine.

13. A starter as characterized, comprising a driven member embodying oppositely-disposed gear teeth in spaced relation; a stationary shaft for rotatively supporting said member; a coil spring connecting said shaft and member; transmission means operatively connected with the crank shaft of an internal combustion engine and embodying a floating gear pinion disposed between the teeth of said member and in spaced relation thereto, said pinion having teeth for engaging the teeth of said member; means for automatically maintaining said pinion in engaged relation to said teeth; selective means manually operative for shifting said pinion to engage one set of said teeth to drive said member from said crank shaft, to wind said spring; a brake shoe set to normally restrain the rotation of said member in response to said spring.
